(57) **CLAIM**

The ornamental design for a display screen or portion thereof with animated graphical user interface as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof; and,

FIG. 6 is the sixth image thereof.

The appearance of the animated graphical user interface transitions sequentially between the images shown in FIGS. 1-6. The process or period in which one image transitions to another forms no part of the claimed design.

The broken line showing of the display screen or portion thereof forms no part of the claimed design.
